UNITED STATES PATENT OFFICE.

SAMUEL S. WILLIAMSON, OF BRIDGEPORT, CONNECTICUT, ASSIGNOR TO THE LIGHTNING CHECK PUNCH COMPANY, OF SAME PLACE.

DESIGN FOR A CHECK-PUNCH CASE.

SPECIFICATION forming part of Design No. 19,532, dated December 24, 1889.

Application filed October 31, 1889. Serial No. 328,650. Term of patent 7 years.

To all whom it may concern:

Be it known that I, SAMUEL S. WILLIAMSON, a citizen of the United States, residing at Bridgeport, in the county of Fairfield and 5 State of Connecticut, have invented and produced a certain new and original Design for Check-Punch Cases, of which the following is a specification, reference being had to the accompanying drawing, forming a part thereof, 10 and which shows a check-punch case conformed and shaped in accordance with my design.

The leading features of the case which comprise my design are the general shape 15 and conformation thereof, whereby a distinctive appearance is imparted thereto, as herein-after set forth.

In the drawing, 1 represents the base portion of the case, whose rear end is rounded, 20 and whose front portion is bounded by a

curved line of greater radius than that which bounds the rear portion. The side lines of the base are substantially straight and convergent toward the rear curve, into which they merge. 2 is the head portion of the case, 25 which rises vertically from the rear end of the base and then projects forward over the latter. The front of this head projection is rounded and has projections 3 3, as shown in the drawing. 30

I claim—

The design for a check-punch case, substantially as shown and described.

In testimony whereof I affix my signature in presence of two witnesses.

SAMUEL S. WILLIAMSON.
